US0D1059329S

(12) **United States Design Patent** (10) Patent No.: **US D1,059,329 S**
(45) Date of Patent: ** Jan. 28, 2025

(54) **BUTTON ACTUATOR**

(71) Applicant: **Georg Schlegel GmbH & Co. KG**,
Dürmentingen (DE)

(72) Inventor: **Torsten Singer**, Gutenzell-Hürbel (DE)

(73) Assignee: **Georg Schlegel GmbH & Co. KG**,
Duermentingen (DE)

(**) Term: **15 Years**

(21) Appl. No.: **35/517,935**

(22) Filed: **Jul. 13, 2023**

(80) **Hague Agreement Data**

Int. Filing Date: **Jul. 13, 2023**

Int. Reg. No.: **DM/230432**

Int. Reg. Date: **Jul. 13, 2023**

Int. Reg. Pub. Date: **Jul. 28, 2023**
